UNITED STATES PATENT OFFICE.

JOHN J. ZARKER, OF WICONISCO, PENNSYLVANIA.

CIGAR-HOLDER.

1,073,457. -

Specification of Letters Patent. Patented Sept. 16, 1913.

Application filed May 29, 1908. Serial No. 435,782.

To all whom it may concern:

Be it known that I, JOHN J. ZARKER, a citizen of the United States, residing at Wiconisco, in the county of Dauphin, State 5 of Pennsylvania, have invented certain new and useful Improvements in Cigar-Holders; and I do hereby declare the following to be a full, clear, and exact description of the invention, such as will enable others skilled in 10 the art to which it appertains to make and use the same.

This invention relates to improvements in cases or holders for cigars and it has for its object to provide a device of this character 15 which may be easily and quickly fitted in the crown of a hat and which will act to hold a number of cigars in such positions as to prevent breaking.

A further object of the invention is to 20 provide a device of an extremely simple character and consequently of manufacture, and one in which displacement will be provided against while the operation of both 25 application of the device to a hat and the removal therefrom, will be extremely easy of accomplishment. This permits of sale of the device to a large number of people who might otherwise not purchase owing to the 30 difficulty of adjustment and consequent efficient operation of the device.

In the drawings forming a portion of this 35 specification and in which like numerals of reference indicate similar parts of the several views, Figure 1 is a perspective view of the device detached from a hat, Fig. 2 is a transverse section through a hat and the device in position therein, Fig. 3 is a view similar to Fig. 1 showing the modification. Fig. 4 is a view similar to Fig. 2 illustrating 40 the use of the modified form.

Referring now to the drawings, the present holder consists of a band of spring metal 5, which is bent into semi-elliptic shape as illustrated, whereby it will conform to the general interior transverse shape of a derby hat 6 illustrated in Fig. 2 of the drawings.

Against the inner face of the bight portion 50 of the curved band, there are secured a series of spring clamping members. Each of these clamping members consists of a spring plate which comprises a straight portion 15 intermediate of its ends to which is engaged a rivet that holds it to the band 5. From the straight portion 15 the sides of 55 the spring plate project at right angles in

parallel relation and in the same direction for a short distance, after which they are curved outwardly in opposite directions with their extremities in spaced relation 60 sufficiently to permit of the passing of a cigar between them by a slight further displacement. Through each end portion of the band 5 there is engaged a sprig 10, the sharpened point of which projects outwardly from the band and a similar sprig 11 is passed upwardly through the band intermediate of its ends and projects above the top space of the band. In applying this device to a derby hat, the ordinary 70 sweat band 13 of the hat is turned down and the band 5 of metal is passed upwardly into the hat so that it will stand with its extremities against the portions of the inner space of the crown against which the sweat 75 band normally stands. The arch of the band 5 extends transversely of the interior of the hat as illustrated. The extremities are held slightly inwardly while the uppermost sprig is pressed into the material of the 80 hat, after which the extremities are released so that their sprigs will sink into the material of the hat and the sweat band is then folded upwardly against the extreme 85 end portions of the band 5. It is of course understood that the ends of the band do not extend sufficiently far below the upper edge of the sweat band to exert pressure 90 against the head of the wearer.

With the device in place as just described, it will be of course understood that the cigars may be pressed between the spaced edges of the several spring clamps, said clamps being opened slightly farther with the fingers if desired to facilitate this operation, after which the spring clamps will return to their normal positions after being released and will clamp and hold the cigars securely to the band 5. It will further be understood that each cigar may be in turn 100 easily and quickly withdrawn from the spring clamp in which it is held. The provision of the sprigs serves to prevent tilting of the band 5 from its proper position, while the spring quality of the band insures a firm seating of the sprigs in the material of the hat under all conditions.

When it is desired to remove the device from the hat, it is only necessary to turn down the sweat band, then to move the extremities of the band 5 toward each other to disengage the corresponding sprigs from

the material of the hat, after which the device may be drawn downwardly from the hat. It will of course be understood that the extremities of the band 5 do not extend sufficiently far down to lie behind the sweat band of the hat and that other modifications of dimensions may be made without departing from the spirit of the invention.

Referring now to Figs. 3 and 4 of the drawings, there is shown a modification of the invention designed for use in connection with a flat-top or a beaver hat. In this form of the invention, in place of the curved band 5, there is employed a band 20 including a central flat portion at the ends of which the band depends to form the spaced legs 21 which rest against the inner faces of the sides of the hat. Sprigs 22 are passed through the extremities of the band 20 and through the center of the top portion to engage in the corresponding portions of the hat to hold the band from slipping. In this form of the invention, the cigar retaining clips are in the form of split tubes of spring metal which are riveted to the flat top portion 20 and the ends at the splits are spaced sufficiently far apart to permit engagement of a cigar between them after they are pressed apart slightly farther. It will be noted that these bands 5 and 20 have sufficient resiliency to at all times keep the spurs in engagement with the material of the hat just above the normal sweat band and that the central spur 11 enables the

bands to be made of narrow material since this spur prevents lateral swinging of the medial portion of the band. Further by reason of this arrangement the ends of the bands are positioned, well above the material portion of the sweat band, so that the size of the hat is not reduced where it fits the wearer's head.

Having thus described the invention what is claimed is:

A cigar holder for hats comprising a narrow strip of resilient material and substantially U-shape in form and of a length sufficient to extend from a point just below but closely adjacent the upper edge of a normal sweat band in a hat to a similar oppositely disposed point, spurs projecting from the outer side of the strip adjacent the ends thereof whereby said spurs may be constantly held in engagement with the material of the hat body by the resiliency of the strip, a medial spur projecting from the outside of the center of the strip and adapted to engage the center of the hat crown whereby lateral oscillation of the strip may be prevented, and clips attached to the strip on the inner side thereof.

In testimony whereof, I affix my signature, in presence of two witnesses.

JOHN J. ZARKER.
